UNITED STATES PATENT OFFICE.

HERSCHEL J. M. BARNHART, OF WHAT CHEER, IOWA.

DESIGN FOR A REIN-GUIDE.

SPECIFICATION forming part of Design No. 32,898, dated July 3, 1900.

Application filed June 1, 1900. Serial No. 18,780. Term of patent 7 years.

To all whom it may concern:

Be it known that I, HERSCHEL J. M. BARNHART, a citizen of the United States, residing at What Cheer, in the county of Keokuk and State of Iowa, have invented and produced a new and original Design for Rein-Guides, of which the following is a specification.

My invention relates to a new and original design for rein-guides and is shown in the accompanying drawings, in which—

Figure 1 is a perspective view; Fig. 2, a front view; Fig. 3, an end view, and Fig. 4 a bottom plan.

The leading feature of my design resides in a rein-guide having a rectangular base portion, from the middle portions of the end members of which extends a segmental ring, a bar spanning the space between the side members of the base portion intermediate the end members, and a conical projection formed thereon pointing to the apex of the ring.

In the accompanying drawings, the reference-numeral 1 indicates the rein-guide hav-

ing a rectangular base portion composed of side members 2, cross end members 3, and with 25 a bar 4 spanning the space between the side members 2, and provided with a conical projection 5, which points toward the apex of the segmental ring 6, that projects or extends from the middle of the end members 3. The 30 side members 2 are concavo-convex longitudinally, as shown.

My design presents a rein-guide of novel, attractive, and distinguished appearance.

Having thus described my invention, what 35 I claim is—

The design for a rein-guide substantially as herein shown and described.

In testimony whereof I have hereunto set my hand in presence of two subscribing witnesses. 40

HERSCHEL J. M. BARNHART.
